UNITED STATES PATENT OFFICE.

JOSEPH A. PUTT, OF CANTON, OHIO, ASSIGNOR OF ONE-HALF TO PORUS M. SNYDER, OF CANTON, OHIO.

HAY-WAGON BRAKE.

SPECIFICATION forming part of Letters Patent No. 712,091, dated October 28, 1902.

Application filed June 24, 1902. Serial No. 113,016. (No model.)

To all whom it may concern:

Be it known that I, JOSEPH A. PUTT, a citizen of the United States, residing at Canton, in the county of Stark and State of Ohio, have 5 invented certain new and useful Improvements in Hay-Wagon Brakes; and I do hereby declare that the following is a full, clear, and exact description of the same, reference being had to the annexed drawings, making 10 a part of this specification, and to the figures of reference marked thereon, in which—

Figure 1 is a side view showing a portion of a wagon and illustrating my brake properly connected. Fig. 2 is a view showing the top 15 or upper end of the ladder, the ratchet-wheel, and dog. Fig. 3 is a view showing the bottom or lower end of the ladder, also showing the bottom or lower end of the brake-chain, winding-rod, and the guide-wheel. Fig. 4 is 20 a view showing the inner side of one of the hay-rack bars. Fig. 5 is a view showing the outer side of a portion of one of the hay-rack side bars and illustrating the position of the guide-pulley bracket and its guide-cap. 25 The present invention has relation to hay-wagon brakes; and it consists in the novel construction hereinafter described, and particularly pointed out in the claim.

Similar numerals of reference indicate corresponding parts in all the figures of the drawings.

In the accompanying drawings, 1 represents a portion of the running-gear of a wagon which is constructed in the ordinary manner 35 and forms no particular part of the present invention, except that the present brake is especially designed to be used upon a hay-rack mounted upon a wagon.

2 and 3 represent the ordinary side bars of 40 a hay-rack and of course are formed of a length to correspond with the length of the rack designed to be constructed. To the front or forward ends of the bars 2 and 3 are attached the socket-plates 4 and 5, which socket- 45 plates are located upon the inner sides of the rack-bars 2 and 3. The socket-plates 4 and 5 are for the purpose of receiving the ends of the ladder-axle 6, to which ladder-axle is attached the ladder-uprights 7, said uprights 50 being formed of the desired length and properly tied together at their upper ends by a

suitable cross-bar 8, and for the purpose of providing proper rungs intermediate cross-bars may be employed. This construction being common needs no specific description. 55

For the purpose of preventing the weakening of the side bars 2 and 3 no apertures are formed in said side bars opposite the ends of the ladder-axle 6; but said ladder-axle is formed of such a length that its ends will 60 stand against the inner faces of the rack-bars 2 and 3.

To the axle 6 is connected the bracket 9, to which bracket the bottom or lower end of the brake-chain winding-rod 9^a is journaled, the 65 upper end of said rod being journaled in the bracket or plate 10 and the upper end thereof provided with the crank 11 and the ratchet-wheel 12, connected thereto.

Upon the outer side of the side bar 2 is 70 connected the bracket 13, which bracket carries the winding-chain guide-pulley 14, and for the purpose of properly covering the pulley 14 and at the same time forming a guide for the brake-winding chain 15 the cap 16 is 75 provided, which cap is connected to the bracket 13, said bracket and cap and the socket-plate 5 being securely connected by means of clamping-bolts 17. The cap 16 serves the double purpose of forming one-half 80 of the bearing for the axle of the guide-pulley 14, by which arrangement the guide-pulley, together with its axle, can be properly connected and held in proper position.

For the purpose of bringing the winding 85 chain 15 in proper position to be wound around the winding-rod 9^a and at the same time extend along the outer side of the side bar 2 the apertures 18 and 19 are provided, the aperture 18 being formed in the side bar 2 and 90 the aperture 19 in the bracket 13.

To the winding chain 15 is attached the spring 20, and to the spring 20 is attached the brake-rod 21, which brake-rod 21 extends rearward and is pivotally connected to the brake-lever 22. The brake-rod 21 and the brake-lever 22, being of ordinary construction, need no specific description; but of course it must be understood that suitable connections are to be made to properly operate the brake-shoes 23. 95

It will be understood that winding the chain around the winding-rod 9^a will draw the brake-

lever 22 forward, at the same time bringing the shoes 23 against the tires of the wagon-wheels 24.

For the purpose of holding the brake-shoe 23 in proper contact with the wheels the ratchet-wheel 12 and its spring-dog 25 are provided, said spring-dog being for the purpose of preventing any backward rotation of the winding-rod 9^a.

10 In brakes for hay-wagons it is of importance that the brake can be operated regardless of the position of the ladder, and in order to accomplish this feature and at the same time bring the different parts of the brake 15 upon the outer side of the rack I extend the winding chain through one of the side bars and provide guide-roller and cap and side winding-chain.

Having fully described my invention, what 20 I claim as new, and desire to secure by Letters Patent, is—

In a hay-wagon brake, the combination of a hay-rack provided with side bars, the side bars provided with socket-plates located upon 25 the inner sides thereof and at their forward ends, a ladder-axle journaled in the socket-

plates the ends thereof abutting against the inner sides of the side bars, a winding-rod secured in brackets, said winding-rod provided with a crank and ratchet-wheel, a dog adapted to engage the ratchet-wheel, a bracket located upon the outside of one of the side bars and provided with a guide-roller, a combined cap and guide-roller-axle bearing located over the bracket and guide-roller, and a winding 30 chain connected at one end to the winding-rod and extended through the side bar having the guide-roller bracket and guide, and the opposite end of said chain connected in operative relation with the brake-lever, and 35 clamping-bolts adapted to hold the bracket and guide-roller cap in fixed relative position, substantially as and for the purpose specified.

In testimony that I claim the above I have 40 hereunto subscribed my name in the presence of two witnesses.

JOSEPH A. PUTT.
